UNITED STATES PATENT OFFICE.

WILLIAM C. CALDWELL, OF CHICAGO, ILLINOIS.

SIRUP-PITCHER.

SPECIFICATION forming part of Letters Patent No. 280,012, dated June 26, 1883.

Application filed February 7, 1883. (No model.)

To all whom it may concern:

Be it known that I, WILLIAM C. CALDWELL, of Chicago, in the county of Cook and State of Illinois, have invented certain new and useful 5 Improvements in Sirup-Pitchers, of which the following, in connection with the accompanying drawings, is a specification.

In the drawings, Figure 1 is a side elevation of a sirup-pitcher embodying my invention. 10 Fig. 2 is a vertical central section thereof. Fig. 3 is a front view of the upper part of the pitcher, showing the drip-box partly removed. Fig. 4 is a vertical central section of the upper part of the pitcher, showing a modification 15 of construction; and Fig. 5 is a perspective representation of the hinge.

Like letters of reference indicate like parts.

My invention relates to that class of sirup-pitchers provided with a pouring lip or rim 20 extending above the rim of the pitcher, and adapted and arranged to be covered by the pitcher-lid. One purpose in view, in constructing these pitchers in the manner referred to, is to prevent the sirup from dripping upon 25 the outside of the pitcher; but the result so aimed at has not always been satisfactorily accomplished. My purpose is to provide additional aids for keeping the outside of the pitcher clear of drippings, and also clear at 30 the hinge; and to these ends my invention consists in the means I employ for the purposes set forth.

A represents the body of the pitcher; B, the pitcher-rim; C, the pouring lip or rim, and D 35 the lid. The lid is hinged to the body, and adapted to shut down over the pouring-lip rim and upon the rim of the body, and when closed it incloses the lip or rim C, which projects above the rim B, as shown. Heretofore 40 the pitcher-rim, by being below and by projecting laterally from the pouring-lip, has caught the drip, and the drippings thus caught have run back into the pitcher through a slot, opening, or space, the said rim being dishing 45 for that purpose.

These parts, so far as now described, are old; but I have not here attempted to show them precisely as heretofore constructed and arranged, as that construction and arrangement 50 is well known, and will be sufficiently obvious when I describe my supplemental or auxiliary

parts, hereinbefore referred to, which I will now proceed to do.

E is a supplemental or auxiliary lip, which I arrange between the pouring lip or rim and the rim of the pitcher. The lip E, I secure, either permanently or removably, to the pitcher. In Figs. 2 and 3 it is represented as permanently secured to the front of the pouring-lip and to the sides of the rim of the body A; but 55 the rear ends of this rim E do not meet, leaving a space or opening, a, for the passage into the body of the pitcher of any of the contents which may be caught by the upper side of the lip E when the sirup is poured out. In these 60 particular respects the lip E performs the function of the rim of the body A as that rim was heretofore employed; but, as is obvious, some 65 of the drippings would nevertheless be liable to drop or run over the front edge of the rim 70 of the pitcher, and hence appear on the outside of the vessel, when no further means were employed to catch the drippings. For this reason I have placed the lip E between the lip C and the rim B, as shown, in order that the 75 drippings may be twice caught or cut off—once by the lip E and again by the said rim—and thus more effectually prevented from contact with the outside of the pitcher. It is not absolutely essential, however, that the drippings 80 caught on the lip E should be drained back into the pitcher in the precise manner shown. As a further auxiliary, in connection with the means employed for catching the drippings, I 85 bulge out the front face of the lip E, as shown at b, thus utilizing the sticking or clinging quality of the sirup for the purpose of causing the thread of drippings to be drawn rearward and away from the edge of the rim B in case such a thread runs down over the bulge b. 90

F is a drip-box, which I have provided for the purpose of gathering the drippings which run down outside of the lip E and are caught upon the rim B. This box is removably applied to the front of the pitcher, and is arranged directly underneath the lip E, the top of the said box being open. The box F is so formed as to present an external appearance of continuity with upper front portion of the pitcher, and is detachably connected thereto in any suitable 95 way, preferably by resting on an inclined seat or shoulder, c, which is lowest at its rear por-

tion, and by means of a fixed lip or lug, *d*, overlapping the upper edge of the back of the said box, as is clearly indicated in Fig. 2. By this means the box *F* may be removed laterally 5 with facility, from time to time, for being emptied of its contents and washed.

In the modification of construction shown in Fig. 4 the permanent lip *E* is retained and a secondary draining-lip, *E'*, is applied to the 10 box *F*; but in this modification of construction the lip *E* is not absolutely essential. In practice the hinge of the lid becomes gummed and sticky, thus sometimes preventing the lid from dropping when released, besides attracting flies 15 and presenting a dirty appearance. To remedy this defect I construct the hinge as follows: *G* is a tubular piece applied to the rear part of the lid. I cut away the back of the piece *G*, as shown at *e*; and *e'* is a slit extending from 20 one end of the piece *G* to the cut-out part *e*. *H* is a strap or strip of metal applied to the rear upper part of the body *A*, and *H'* is a cylindrical piece applied to the upper end of the strip *H*. The part *H'* is adapted to enter and 25 turn in the part *G*, and the slit *e'* is of such a width as to receive the strip *H* laterally, in order that the part *H'* may be arranged in the part *G*. On the part *H'* is a pivoted button, *I*, the upper end of which is in contact with 30 part *G* when the lid is raised, and thereby prevents the lid from being accidentally detached by being moved laterally; but to remove the lid I turn the button *I* horizontally, when the lid and part *G* may be drawn laterally from 35 the part *H'*, the strip *H* then being in the same plane with the slit *e'*. By this means the lid may be removed with facility for being washed.

Having thus described my invention, what I claim as new, and desire to secure by Letters Patent, is—

1. In a sirup-pitcher having a pouring-lip extending above a body-rim surrounding the said lip, a drip-catching lip arranged between the pouring-lip and the body-rim, substantially as and for the purposes specified. 40

2. In a sirup-pitcher, a drip-catching lip having an outward bulge, *b*, and arranged between a pouring-lip and the rim of the pitcher, substantially as and for the purposes specified. 45

3. In a sirup-pitcher provided with a drip-catching lip, a removable drip-gathering box open at the top and arranged underneath the said lip, substantially as and for the purposes specified. 50

4. The combination, in a sirup-pitcher having a pouring-lip, of a removable drip-gathering box open at the top and arranged underneath the said lip, and a bulging-lip for catching the drip and drawing it into the said box, substantially as and for the purposes specified. 55

5. The combination of the tubular part *G*, applied to the lid of the pitcher, and having therein the cut-away portion *e* and the slit *e'*, the strip *H*, applied to the body of the pitcher and having on its upper end the piece *H'*, adapted to enter and turn in the part *G*, and the pivoted button *I*, applied to the strip *H*, substantially as and for the purposes specified. 60

WILLIAM C. CALDWELL.
